ABSTRACT

An ingot casting apparatus in which protecting gases used in melting metals are introduced into a sealed casting vessel through a specially design sealed ladle or tundish connected with the vessel and through a spout of the remelting furnace which is also connected with the ladle or tundish in a completely gas-sealed condition, and molten metal is cast under an evacuated or inert gas atmosphere.

INGOT CASTING APPARATUS

This invention relates to a ingot casting apparatus employing a furnace gas which is generated in the refining period as protecting gas in the casting.

The apparatus consists of a specially designed tundish or ladle equipped with a gas-sealed cover connected with a furnace spout and a gas sealed vessel in which an ingot mold is installed.

This vessel is used under conditions when it is full of an inert gas atmosphere or a vacuum, introduced through a specially designed tundish or ladle.

Many reports or inventions have been published on the various methods and apparatus which have been used for ingot casting in neutral or inert gas atmospheres.

Especially for obtaining lower undesirable inclusions, the following methods and apparatus are used:

1. A method which prevents the molten steel from oxidizing by blowing inert gas along with the stream of molten steel being teemed,

2. A method which prevents molten steel from segregation by blowing inert gas into the molten steel with or without slag and stirring the steel by an induction coil;

3. A method which keeps a certain pressure in the mold by means of blowing a neutral or inert gas into the molten steel in the mold, thereby to obtain a round ingot;

4. method of casting the metal in a gas-curtain along the bottom and inner surfaces of mold in order to prevent the surface defects in the ingot;

5. An apparatus in which an inner gas conduit extends nearly to the bottom of the ingot mold in order to reduce splashing in the metal casting in the inert gas atmosphere.

The apparatus of the present invention is quite different from the above mentioned methods and apparatus.

This invention relates to ingot casting apparatus which comprises a specially designed tundish or ladle equipped with a gas sealed cover which is connected with a spout of the special remelting furnace (for example, a plasma arc furnace) which is enclosed by an inert or neutral atmosphere gas and can be freely adjustable, those gases being for example, Ar or N₂ gas, and a gas sealed vessel in which an ingot mold is installed.

Therefore, according to the apparatus of the present invention, the atmospheric gas used in the remelting furnace is introduced through the spout and, covered tundish or ladle into the sealed vessel. This vessel can be used under vacuum.

The purpose of this invention is to resolve the following problems of conventional metal casting by using a special atmosphere in a remelting furnace gas and protecting gas. Those problems in conventional castings are:

1. Increased inclusions or gases in the high purity metal because of teeming in the air.

2. In general, the protected gas casting cost is somewhat higher than ordinary casting in the air, because much high cost inert gas is used.

Detailed structure of the present apparatus is explained hereunder in accordance with the drawings.

In FIG. 1, the spout FA of the plasma arc furnace F and the cover of the tundish 1 are connected and sealed by bellows 3b and the tundish 1, teeming tube 7, and

the casting vessel 6 are connected and sealed by bellows 5.

While an evacuation system is operated, the air in the tundish 1 and vessel 6 is evacuated.

5 In a meantime, inert gas is supplied from the plasma jet torch into the plasma arc furnace F, therefore this inert gas is introduced into the vessel 6 through the spout FA, tundish 1, tundish nozzle 2 and evacuated to the outerside through an evacuation system.

10 After checking the displacement of the air in the vessel with the inert gas, valve 10 is shut and the vessel 6 remains filled with the inert gas.

If indicated pressure at safety valves 4 and 9 becomes 15 higher than the previously set pressure, then the valves are opened automatically and the inert gas in the vessel 6 is exhausted to the outside.

20 After that, the remelting furnace F is tilted just in the direction indicated by the arrow mark, and the high quality metals excluding inclusion are teemed into the tundish 1 through the spout FA and introduced into the nozzle 2, teeming tube 7 and finally to the ingot mold 8 which is complete protected by the inert gas atmosphere.

25 As the metals are cast in the above process, clean ingots are obtained without non-metallic inclusions and also without increments of gases in the metals.

The lower casting cost are obtained by the inventive 30 method rather than by conventional inert gas protected casting methods. When vacuum casting is desired, just as shown in FIG. 2, the tundish 1 and the vessel 6 are closed, by inserting a meltable metal plate, which is a little larger than the inner diameter of the nozzle 2, into 35 the bottom of the nozzle 2 and fastening it by bolts 12b.

Thereafter, the air in the vessel 6 is evacuated by 40 operation of an evacuation system and the desired pressure in the vessel 6 is confirmed by the safety valve 9.

In the meantime, the air in the tundish 1 is converted 45 by continuously supplying inert gas from the plasma jet torch through plasma arc furnace F, the spout FA and tundish 1, therefore the tundish 1 is filled with the inert gas and the pressure in the tundish increases.

But as soon as the pressure reaches a set pressure on 45 the safety valve 4, the valve is opened and the mixture of the air and inert gas is discharged.

Hence, the displacement of the air in the tundish 1 by 50 inert gas is confirmed.

55 After that, the remelting furnace is tilted just in direction by the arrow mark and the molten metal refined and alloyed in the furnace is teemed into the tundish 1 which is filled with inert gas and the pressure is maintained below a set value.

The hot metal melts the metallic plate 12 and is introduced into the vessel 6 becoming fine droplets in the 60 vacuum therein, and finally filling the ingot mold 8 through teeming tube 7.

As a result of the above mentioned process, the purity of the metal is increased and gas volume in the metal is minimized. These casting operations in the inert gas or vacuum are inspected through a inspection hole 11 mounted on the upper side of the vessel 6.

65 Moreover, by high temperature gas supplied from the remelting furnace, tundish 1 is preheated up to about 500° - 600° C and ingot mold 8 is heated to about 300° - 400° C. That preheating improves ingot casting.

This apparatus is intended to be used for atmosphere remelting and for re-circulating the inert gas which is discharged from the remelt zone.

Even the comparably simple structure of this apparatus can prevent contamination of the molten metal by the air and at the same time can preheat the tundish 1 and ingot mold 8, and moreover this apparatus has characteristics which can produce clean ingots at lower cost.

What we claim is as follows:

1. An ingot casting apparatus, comprising:
a plasma arc melting furnace,
a tundish associated with the output spout of said furnace,
a casting vessel enclosing a casting mold associated with the tundish,
first bellows connecting and sealing the spout of said

furnace and the cover of said tundish,
second bellows connecting and sealing the outlet of said tundish and the top of said casting vessel, the output spout providing means for tapping molten metal from the furnace to the tundish and also providing means for circulating the inert gas from the furnace into the tundish and the casting vessel, and means for evacuating said casting vessel.

2. The apparatus of claim 1 wherein said furnace is rotatably mounted so that it may be tilted to tap molten metal from said furnace into said tundish.
3. The apparatus of claim 1 additionally comprising a melttable metal plate closing the outlet of the tundish.
4. The apparatus of claim 1 wherein said casting mold additionally comprises a teeming tube aligned below the tundish outlet.
